(57) **CLAIM**

The ornamental design for a toy pop gun ball launcher, as shown and described.

DESCRIPTION

FIG. 1 is left side view of a toy pop gun ball launcher, the right side view being a mirror image thereof;

FIG. 2 is a top view thereof;

FIG. 3 is a bottom view thereof;

FIG. 4 is a front view thereof;

FIG. 5 is a rear view thereof; and,

FIG. 6 is a perspective view thereof.

The area encompassed by broken lines in the drawing depict portions of the toy pop gun with barrel handle that form no part of the claimed design.
